UNITED STATES PATENT OFFICE

WALTER G. SEABOLD, SR., OF ALTON, ILLINOIS

BOX OR CRATE STRUCTURE

Application filed May 14, 1930. Serial No. 452,301.

The present invention relates to boxes, crates, enclosures and the like, having particular reference to a knock-down structure, which may be provided in units of parts for assembly into a rigid structure.

The invention aims to provide a structure which can be made economically and sold, transported and stored in knock-down form, for assembly without the use of a tool in that operation. It is a particular object to provide a series of simple units that may be quickly assembled into a rigid compact box.

Such an assembled box may be packed, as in a shipping room of a department store, and sealed for shipment, by inexperienced help, without the use of a tool, without pounding, without effort, and rapidly without any waste of time.

Another feature of the invention is the provision of sides or panels separate from the bottom and top of the box, whereby various heights and kinds of panels, and of tops and bottoms may be assembled to provide different sizes and different kinds of structures as the circumstances may require.

Another feature of the box is the fact that it may be made of wood, using thin and small pieces to build up parts for the structure, by rapid methods of production, making the structure economically practical, with the use of standard wood mill equipment. It is therefore a particular object to provide a wooden box.

Various other objects and advantages of the invention will be apparent from the following description of an exemplary embodiment thereof shown in the accompanying drawings, in which

Fig. 1 represents a vertical cross-section of a box on line 1—1 of Fig. 2.

Fig. 2 is a vertical cross-section taken on line 2—2 of Fig. 1.

Fig. 3 is a perspective view of the cover from the underside, as it would appear lifted from the position in Fig. 1.

Fig. 4 is a perspective view of the box bottom with the sides removed.

Fig. 5 is a view of the outside of a long side panel.

Fig. 6 is a view of the outside of a short side panel, or the front panels of Fig. 2.

Fig. 7 is a view of the inside of a short side panel, on the rear panel of Fig. 1.

Fig. 8 is a view of the inside of a long panel.

Fig. 9 is an enlarged detail view of a top corner of the assembled panels showing a locking means.

Although I have hereinafter disclosed and specifically described a wooden box of the closed type it is to be understood that the invention is not thus limited to a closed box, nor to any specific material, nor structure, and that various modifications and changes in construction are herein contemplated, as will fall within the scope of the invention as it is expressed in the appended claims.

The illustrative box of the drawings has a base 10 in the form of a closed area made up of thin wood stock pieced together and secured to base skids or cleats 11 and 12, as by nails or other means known to the art. It will be noted that the cleats 11 and 12 project beyond the edges 13 and 14 of the base 10. At the edges of the projecting cleats, upright horizontal rails 15 and 16 are secured, each of which has an internal recess 17 therein forming on the sides an inwardly projecting hook-like structure with a retaining rib 18. The ends of cleats 11 and 12 project beyond the base 10 as do the sides of the cleats. The ends are indicated in Fig. 2 at 19 and 20. Across ends 19 and 20 are secured other recessed rails 21 and 21^a, like rails 15 and 16, the four latter rails forming a rectangular frame enclosure, shown in Fig. 4. Within the frame there is thus formed a rectangular channel or recess by the individual recesses 17 in the four rails. Within the frame opposite the recess sets the base 10, above the bottom level of the recess.

It will also be noted that the inside of rib 18, relative to the inside of the box, is beyond the outside parallel edge of the base 10, by a width sufficient to form a thickness for a box wall or side, and that the rib 18 is elevated above the bottom 10 to permit insertion of a panel, as will appear hereinafter.

The box walls or sides are made in remov-

able units or panels, which are shown as closed areas for a closed box, or which may be open for a crate. Two long panels and two short panels are provided, for the rectangular box 5 illustrated. The short ones fit between the long ones and hold them apart in spaced relation. Each panel is provided with a structure which cooperates with a rib 18, recess 17, and an edge of base 10 to hold the panel immovably fixed vertically and horizontally. The two long panels are identical and interchangeable, and the two short panels have a similar relation. Fig. 5 shows the outer side 10 of a long panel 22, and Fig. 8 represents a view of the inner side. The outer side has a cross strip 23 at the bottom which fits into recess 17. It is slightly rounded or bevelled at the corners 24 and 25 to permit the panel 15 to be inserted angularly into position by a planar movement as shown by the dotted line position 26 in Fig. 1, from which angular position it may be swung into final position. The strip in the recess acts as a sort of pivotal axis for the swinging and the parts co- 20 operate to effect positive engagement. The top of the panel has a cross strip 27 which is longer than the panel, to cover the ends of a similar cross strip on the shorter panels, or the box ends. Cross strips 23 and 27 may 25 be stitched by wires to small pieces of stock to build up a closed panel or a crate side.

Short panels 30 are shown in Fig. 7 which indicates the inner side of the rear wall (as 30 viewed in Fig. 1) and in Fig. 6 which indicates the outer side of the front wall. Each is formed like the side panels with bottom cross strip 31 and top cross strip 32. After the long side panels are positioned the short side panels are similarly placed in position, 35 the slightly projecting ends of top cross-strips 32 slightly spreading the panels outwardly from normal position. The rigidity of the inter-fitting parts holds the panels in normal position, but they may be ordinarily free to be sprung outwardly. The projecting ends of cross strips 32 and 27 (see Fig. 9) 40 positively prevent either panel being forced inwardly.

In order positively to position the panels 45 against outward movement a locking means may be provided. In the present instance this is made of cheap, simple and generally inefficient construction, because its useful effect is but a temporary one when the box is used in connection with a cover similar to that shown in the illustration. However, the same corner holding construction could be made more permanent in character, or be altered in form for other purposes.

On the end panels I provide an L-shaped hook 33, mounted by a pin, rivet or screw 34 to turn thereon. The long panel 32 is slotted 50 as at 35 to receive the hook edgewise. Each corner may have a locking means.

Given the box described, any suitable cover

or closure may be used, but I prefer to use one of certain structure which makes the complete box capable of assembly without a tool. The box which is shown in the drawings is constructed of light weight material 70 and the panels are somewhat resilient, that is, with the corners fixed, the sides may be slightly flexed inwardly away from the normal position. I provide a cover which has a cap construction capable of fitting over the 75 box at the box top, defined by a frame comprising the top cross-strips 32 and 27 of the panels.

The cover has a rectangular frame formed of members 40, 41, 42 and 43 covered by a 80 closure of boards 44. Two opposite frame members have each an inwardly projecting rib 45 at a central portion thereof, but not at the ends, which rib is adapted to fit under the top cross-strips 32 and/or 27 to lock the 85 cover onto the box. The rib is bevelled at 46 to provide a cam for flexing the panels inwardly to place the cover into its self-locking position.

Because wood is by far the most common 90 material used for boxes, and because of the character of machinery used for operations on wood, it will be observed that the functional parts of the box herein described are shown in elongated form from corner to corner of the box. Such extent of functional surface or construction is preferable for strength and rigidity, but it is obviously unnecessary, and much of the disclosed parts might be eliminated and many made discontinuous, or the relative locations may be 95 changed, without departure from the spirit and scope of the invention. For example:

The strips 21^a, 16, 21 and 15 form a frame, 100 which has no essential function as a frame. For each panel two spaced portions of each strip only are necessary. These may be combined as corner pieces, thus eliminating the central portion of each of the frame members.

The perimetric recess 17 shown inside the 110 frame receives and retains the panel strips like 31 by the action of rib 22. The functional parts are the hook structure formed by the rib 22 with the recess 17 and an upwardly facing surface on the panel to be engaged by the hook, as is formed by the strip 31.

In a crate, or other structure the boards which form the bottom of the closed box may be omitted and an open structure provided, using, for example, the two end boards of 120 which the illustrated bottom is composed. Each of these functions at its ends as stop means against inward motion of the long panel, and at its edge as a similar means for a short panel.

It will be understood that the sides, top and bottom may be open to form a crate, or may be formed of screening paper, fiber board or otherwise constructed without de- 130

parture from the spirit and scope of the invention. The locking means at the corners may be readily dispensed with, as the cover itself will positively prevent any outward displacement of the box sides. Although the cover is not active for this purpose while the box is being packed, the box sides may be fixed against such outward motion in packing by placing the box in a vice, a form, or 10 a frame until the cover is placed in position.

The invention is not limited to side walls which flex inwardly to permit placing the cover in position, for it is possible to make the side retaining frame members of the 15 cover the flexible parts, or to make them rigid, and provide a different and resilient rib or structure to function like rib 45 when the cover is fixed on the box.

The invention contemplated by this application is generally the whole box including cover which can be assembled without a tool, and more specifically, the open box (without cover) which may be assembled without a tool, as well as the novel box bottom itself, the novel panels, and the novel structure and relation existing between each panel and the bottom.

What I claim is:

1. A box-like structure having component 30 parts assembled into self-holding form, comprising a base providing a bottom for the box, vertical upright means secured to said base providing a recess bounded laterally by a portion of the base and the upright means 35 and bounded vertically by a portion of the base and the upright means, and panels which form the box sides, each panel having thereon outwardly projecting means for cooperation with the upright means to hold 40 the panel in position to form the box, said panel and the projecting means thereon being adapted when fitted into position to have the projecting means and a portion of the panel located in said recess.

45 2. A box-like structure having component parts assembled into self-holding form, comprising a base providing a bottom for the box, vertical upright means secured to said base providing a recess bounded laterally by 50 a portion of the base and the upright means and bounded vertically by a portion of the base and the upright means, panels which form the box sides, each panel having thereon outwardly projecting means for cooperation 55 with the upright means to hold the panel in position to form the box, said panel and the projecting means thereon being adapted when fitted into position to have the projecting means and a portion of the panel located 60 in said recess, and means to hold the panels together against swinging motion about the line of the coacting parts.

65 3. A box-like structure having component parts assembled into self-holding form, comprising a base, providing the bottom, panels

for forming the sides, said panels being located laterally of and about the bottom, a projection horizontally on the outside of each panel near the bottom thereof, and means secured to the base extending outwardly, upwardly and inwardly as a hook over said projection to secure each panel against vertical motion. 70

4. In a box-like structure having component parts assembled into self-holding form, 75 a base structure comprising a bottom member, hooked means carried by said member extending from a point below the top level of the base to a point beyond the bounds of the base, upwardly therefrom, and then inwardly to a point outside the bounds of the base. 80

5. In a box-like structure having component parts assembled into self-holding form, 85 a base structure comprising bottom means forming a perimetric bound for the interior of the box, and a frame carried by said means outside of said bound, said frame being internally recessed opposite said bound, said recess extending perpendicularly to the plane of said frame to a point above the upper side 90 of said bottom means.

6. In a box-like structure having component parts assembled into a self-holding form, 95 four side panels for said box, each panel having means adapted to hold it to the bottom of the box, two panels being located in the box between the two other panels, and means on the outside of said first two panels extending beyond the width of said panels and overlying the edges of the other two panels. 100

7. In a box-like structure having component parts assembled into a self-holding form, comprising a bottom member, panels forming side walls, cooperating means contained within the inner and outer peripheral 105 confines of the box one part being on the bottom member and one part being on each panel for holding the panel vertically and horizontally immovable with respect to the bottom member, yet permitting inward swinging movement of the top of each panel into the box, whereby the cooperating means become disengaged to permit withdrawal of the panel along the plane thereof at an angle to the bottom, and means on the panels holding each panel against such inward swinging of the panel. 110

8. In a box-like structure having component parts assembled into a self-holding form, 120 comprising a bottom member, panels forming side walls, cooperating means, contained within the inner and outer peripheral confines of the box one part being on the bottom member and one part being on each panel for holding the panel vertically and horizontally immovable with respect to the bottom member, yet permitting inward swinging movement of the top of each panel into the box, whereby the cooperating means become 125 disengaged to permit withdrawal of the panel 130

along the plane thereof at an angle to the bottom, and strips paralleling and adjacent the top edges of each panel projecting beyond the panel forming members of a frame about said panels.

5. 9. In a box-like structure, a box bottom, a panel, and cooperating means on the panel and the bottom for mounting the panel vertically and horizontally immovable relative to the bottom, said means comprising a retainer carried by the bottom beyond the bottom providing a space between the retainer and the bottom, and providing an inwardly extending hook-structure, said panel being adapted in form to fit into said recess and presenting an upwardly facing surface for engagement by the hook.

10. 10. In a box-like structure having component parts assembled into self-holding form, a base structure comprising a rigid frame having narrow frame members, with a recess on the inner side of each frame member, skid-like members on one face of the frame as a support for the structure, stop means carried by said skids and located inwardly of the frame opposite a recess for cooperation therewith to hold other parts of the structure.

In testimony whereof I have hereunto affixed my signature.
